UNITED STATES PATENT OFFICE.

LEE H. PAYNE, OF CHICAGO, ILLINOIS.

BOTTLE CRATE.

1,420,444.

Specification of Letters Patent. Patented June 20, 1922.

Application filed March 22, 1920. Serial No. 367,730.

To all whom it may concern:

Be it known that I, LEE H. PAYNE, a citizen of the United States, residing at Chicago, in the county of Cook and State of Illinois, have invented certain new and useful 5 Improvements in Bottle Crates, of which the following is a specification.

This invention relates to crates for holding bottles, and particularly to that type of 10 crates in which the walls of the pockets are developed by crossing flat strips of metal having their ends anchored into the side and end walls of the crate, and in which the bottoms of the pockets are provided by metal 15 strips running beneath the pockets.

The object of the present invention is to develop a more rigid construction of pocket walls from the crossing strips of metal; also to develop a construction of supporting 20 strips or bottoms which will better protect the bottles resting thereon. Accordingly, one feature of the present invention consists in arranging the strips of metal, which are to form the walls of the pockets, with 25 their greater dimension extending vertically, and with the strips intersecting one another so that the upper and lower edges of the crossing strips are in substantially the same planes, the strips being notched one into the 30 other at the points of intersection so that they become mutually sustaining vertically as well as horizontally, and the ends of the strips being firmly anchored in opposed 35 walls of the crate so that the strips remain under a measure of tension and each group of intersecting partition strips becomes a unitary suspension structure.

Another feature consists in corrugating the strips that form the bottom of the 40 pockets with their waves extending vertically, so that when the bottom strips are anchored between opposed walls of the crate they may be put under considerable tension, permitted by the longitudinal resiliency of 45 the strip, and thus made to absorb shocks incident to dropping bottles upon them and avoid stretching downwardly, and with the further assurance that in the event of distortion of the bottom by improper handling 50 or by intrusion of some projecting object upward into the bottom space, the vertical dimension developed by the corrugated strip will be such as to keep the bottle from contact with the ground or other object even 55 though the bottom strip should sag into contact therewith at one or more points.

The invention will be fully understood upon reference to the accompanying drawing, in which—

Figures 1, 2, and 3, are, respectively, a perspective view, a longitudinal section, and a transverse section of a crate embodying the several features of the present invention.

1 represents the opposed end walls, and 2 the opposed side walls of a crate, preferably made of wood and constructed in accordance with my United States Letters Patent No. 1,331,364, issued February 17th, 1920. Firmly anchored in the end walls 1 and tightly stretched between said walls are longitudinal partitions 3, which stand with their greater dimension vertical for the greater portion of their length, their extreme ends, however, being twisted through an angle of 90° to present the greater dimension horizontally as the ends enter the wall of the crate for anchorage. Intersecting the longitudinal partitions 3 are transverse partitions 4 similarly arranged with their greater dimension vertical for the greater 70 portion of their length, but preferably having their ends deflected to present the greater dimension horizontally where the ends enter into anchoring relation with the side walls 2 of the crate. These transverse 75 partitions are likewise stretched tightly between the opposed walls in which they are anchored. The partition strips 3 and 4 are oppositely notched at their crossings 5 so that they may intersect and lie between the 80 same horizontal planes and become mutually sustaining not only against lateral displacement, but vertically as well. That is to say, 85 the notches are proportioned so that the thickness of the metal of one strip fits snugly into the notch formed in the other strip; and in addition to each strip being firmly anchored against displacement laterally to itself and longitudinally of the other strip, any load which tends to depress the strips 90 vertically will cause the walls of the upwardly presented notch to press firmly against the intersecting strip, with consequent stiffening of the whole structure.

The bottom strips 6 have their greater 105 dimension extended horizontally, with their ends firmly anchored in the end walls 1 of the crate, and with corrugations extending preferably from end to end but at least to an extent which presents a series of corrugations 110 to receive the bottom of each bottle. With this construction of bottom strips, the

strips may be introduced under considerable tension, and this tension will be maintained by the longitudinal resiliency of the strips, so that tendency of the metal of the strips to 5 take on a permanent set under the constant dropping of the bottles upon them will be minimized, and even in case the strips beneath a given pocket should, by violence, be bent downwardly until the corrugations rest 10 upon the ground, or some unevenness that intrudes upward into contact with the bottom strip, the strips will still hold the bottle out of contact with the ground or intruding object.

15 I claim:

A bottle crate comprising rigid sustaining

walls, pockets formed by partitions extending between said walls, and bottoms beneath said pockets sustained by said walls and comprising thin metal strips disposed with 20 their greater transverse dimension horizontal and their broader faces in position to receive the impact of bottles dropped into the pockets; said strips being corrugated vertically to develop longitudinal resiliency 25 therein and having their ends anchored in opposed walls of the crate under initial longitudinal tension and being otherwise free from vertical restraint between their ends.

Signed at Chicago, Illinois, this 15th day 30 of March, 1920.

LEE H. PAYNE.
